SLAT CLASP FOR VENETIAN BLINDS

Carl V. Newbill, Portland, Oreg.

Application April 14, 1945, Serial No. 588,361

1 Claim. (CL. 160—173)

1

This invention relates generally to Venetian blinds and particularly to a slat therefor.

The main object of this invention is to provide an improved form of blind slat which will be readily removable for cleansing purposes, painting, or repairs.

The second object is to provide a slat of the class described, which will possess all of the strength of the conventional form of slat and without detracting from the appearance thereof.

I accomplish these and other objects in a manner set forth in the following specification as illustrated in the accompanying drawing, in which

Fig. 1 is a fragmentary plan of a portion of a blind slat showing an open cord slot and a wire closure therefor.

Fig. 2 is an edge elevation of Fig. 1.

Fig. 3 is a transverse section taken along the line 3—3 in Fig. 1.

Fig. 4 is a view similar to Fig. 1, showing a modified form of closure.

Fig. 5 is an edge view of Fig. 4.

Fig. 6 is a section taken along the line 6—6 in Fig. 4.

Fig. 7 is a fragmentary plan of a prior art slat.

Similar numerals refer to similar parts throughout the several views.

Referring in detail to the drawing, there is shown in Figs. 1 to 3 a slat 10 having a slot 11 formed therethrough from one edge 12 to receive the cord 13. In order to strengthen this slat the corners 14 and 15 are joined by a wire clip having the two side members 16 and 17, which are united at one end by the U-shaped member 18 and the opposite ends of the members 16 and 17 having the U-shaped clamps 19 and 20 formed thereon, whose tips 21 are preferably curled backwardly as shown.

The material from which this device is made is preferably a spring steel wire, which is frictionally held in place by the spring action of the U-shaped members 18, 19 and 20. It can be seen that should it be desirable to remove the slat 10 from the cords 13, it is only necessary to slip

the clamps off of the slat and withdraw it laterally.

In the form of the device shown in Figs. 4 to 6, the slat 10 is also provided with a slot 11 for the cord 13 and the mouth of the slot 11 is closed by the channel shaped spring clamp 22, whose middle portion 23 is preferably inturned into the slot 11 to serve as a means for locating the clamp 22 along the slat 10, and also to protect the cord 13 from the edges of the metal in the clamp 22. In Fig. 7 there is shown the common form of prior art slat 24, in which the slot 25 does not extend through the side of the slat. That is, it is not an open slot. It can be seen that in either of the forms of the device shown in Figs. 1 or 4, the principle employed is the same, the difference being only in the form of material used. In either case, it will be desirable to finish the material in the clamp to correspond with the finish of the slat 10 itself.

It will be noted in Fig. 3 that the intermediate portion 26 of the members 16 and 17 is bent inwardly to occupy the slots 11. The purpose of this construction is to fix the longitudinal position of the device with relation to the slot 11.

While I have thus illustrated and described my invention, it is not my desire to be limited to the precise form shown herein, and I intend to cover such forms and modifications of the invention as fall fairly within the appended claim.

I claim:

A clasp for blind slats consisting of an elongated channel having the intermediate portion of its upper side inturned to form a closure across a portion of the open side of said channel.

CARL V. NEWBILL.
